UNITED STATES PATENT OFFICE.

STEPHAN SCHNEIDER, OF BERLIN, GERMANY, ASSIGNOR TO GENERAL ELECTRIC COMPANY,
A CORPORATION OF NEW YORK.

WATER-JET GROUNDER FOR PROTECTION AGAINST EXCESSIVE POTENTIALS IN ELECTRICAL SYSTEMS.

No. 866,075.

Specification of Letters Patent.

Patented Sept. 17, 1907.

Application filed January 26, 1907. Serial No. 354,280.

To all whom it may concern:

Be it known that I, STEPHAN SCHNEIDER, a subject of the Emperor of Austria, residing at Berlin, Germany, have invented certain new and useful Improvements 5 in Water-Jet Grounders for Protection Against Excessive Potentials in Electrical Systems, of which the following is a specification.

Of the various devices for protection against excessive potentials and lightning in electrical supply systems, water-jet grounders have recently found particularly wide use on account of their satisfactory operation. These are for the most part arranged in a manner such that a continuous jet of water is directed against a metallic plate connected with the electrical conductor, or a column of water flowing through an insulating pipe is utilized as an inductionless resistance between conductor and earth. By means of this continuous grounding, any potential can be carried off as soon as it appears, and it is not required, as is the case with 10 spark-gaps, to reach a certain bridging potential. It is inherent in the nature of the forms of these water-jet grounders known up to the present time, that a constant loss of energy must ensue, apart from the consumption of water. Attempts have been made to 15 control the latter by introducing self-cooling, circulation-water-resistances; the consumption of electric energy it has not yet been possible to avoid.

The object of the invention is a water-jet grounder which avoids the constant consumption of electric energy and has the advantage that the water losses are slight. This is attained by grounding the water-jet only at the moment of the occurrence of an excessive potential by means of this latter itself.

In the testing of high-potential insulators with artificial rain, it has been observed that the statically charged water drops which flow down from the edge of the insulating bell, are attracted by means of the opposite charge of the grounded support and hereby grounding is produced between conductor and support. 20 The injurious effect in this case of the statically charged jets of water is, according to the invention, utilized for the construction of a water-jet grounder of the properties stated at the beginning.

Figure 1 shows a protective device in which one of the electrodes consists of a jet or stream of water movable toward a second electrode by electrostatic attraction; Fig. 2 shows a modified form provided with a horn gap.

In Fig. 1 a slender jet of water 1 falls to earth by gravity near a sheet metal plate 2 attached to a supply conductor or line wire 3. If now, an excessive potential arises on the line conductor, the potential of the sheet metal plate 2 rises and draws the water jet over

to decrease the distance between the jet and plate. If the initial distance between plate and jet is suitably 55 adjusted, the attraction may be carried to the point of mutual contact, or at least so far that between plate and jet a discharge takes place and thus connects the plate with earth.

Instead of a falling jet of water there may, of course, 60 be employed a rising one; instead of an individual jet, a number thereof, or a broad band of water in any desired position with relation to the electrode surface.

The modification shown in Fig. 2 comprises a bolt 4 for connection with the line conductor to be protected, 65 and carrying at one end a sheet metal plate 5 rotatable about the point 6 as a pivot and bent in horn shape. All of the above-mentioned parts are suitably insulated from ground by the insulator 7. The water outlet, or nozzle, 8, which is likewise formed horn-shape, 70 has a valve 9 with a jet regulator 10 for securing good contraction in the jet of water. An insulating pipe 11 is attached to the water jet or nozzle and serves as a means for supplying water thereto from the water main 12. Excessive potentials of small magnitude are generally carried through the jet of water 13 to earth, while 75 very heavy discharges may pass the spark-gap between the horns and be conducted off through the water in the insulating tube 11. This water therefore, serves the function of the resistance heretofore used with lightning arresters to restrict the flow of line current following the discharge. The electrical resistance of the jet of water 13 will usually be considerably higher than that of the water contained in the insulating tube 11; the former thus exerts only a slight influence on the latter. 80

Since in the new water-jet grounder there is no constant loss of electrical energy, the water will always have only a slightly increased temperature, and will, therefore, possess a great heat capacity. In order to still further restrict the consumption of water, the 90 water may be caught in a tank 14 and be forced back into the pipe 12 by means of a pump.

The force exerted on the water jet may be still further increased by arranging a ground plate on the side opposite the plate 5, in which case the repulsion by 95 reason of the ground plate is added to the attraction caused by the potential of the system. Also, with the use of an insulating tube between water conduit and exit or outlet, the water jet may be permitted to flow from the supply conductor to earth, whereby all dropping particles of water are attracted by the ground plate and repelled by the plate subjected to the potential of the system. 100

It should be noted that the above-described arrangements are not the only ones possible, but that of course, 105 constructive modifications of the individual parts may

be made, especially as relates to the form and composition of the electrodes and the position of the jet of water with relation to its nozzle and its electrodes. Thus, for example, it is possible to form the metallic plate and band of water as cylindrical surfaces of different curvature, so that the distance of the individual elements of the band of water from the oppositely situated elements of the metallic surfaces is different, and according to the magnitude of the excess potentials, a larger or smaller portion of the band of water is attracted.

What I claim as new and desire to secure by Letters Patent of the United States is,—

- 15 1. The combination with a conductor to be protected, of a water-jet, and a plate in proximity thereto for changing the position of the water jet to produce a conductive path for the discharge of excess potential arising on said conductor.
- 20 2. The combination with an electrical conductor to be protected from excess potentials, of a plate connected thereto, means for maintaining a fluid stream within the electrostatic field of said plate, but normally out of contact therewith, and a ground connection for said stream.
- 25 3. The combination with a line conductor to be protected from excess potentials, of a plate connected therewith and establishing an electrostatic field, means for maintaining a jet of water in proximity to said plate and in position to be attracted by said plate when an abnormal potential occurs on said conductor.
- 30 4. The combination with a line conductor to be pro-

tected from high potential strains, of a plate connected therewith, and means for maintaining a jet of water in proximity to said plate but normally out of contact therewith, said jet of water being grounded.

5. A protective device comprising a spark gap formed between a conductive plate and a stream of conductive fluid, the length of said gap being automatically controlled by the electrostatic charge of said plate.

6. In a protective device, the combination of a spark gap formed between a conductive plate and a fluid supplying nozzle delivering a stream of liquid in proximity to said plate but normally out of contact therewith, and projections from said plate and nozzle forming a horn gap.

7. In a protective device, the combination of a spark gap formed between a conductive plate and a fluid supplying nozzle delivering a stream of liquid in proximity to said plate but normally out of contact therewith, projections from said plate and nozzle forming a horn gap, and a section of insulating pipe separating said nozzle from the source of liquid supply.

8. A protective device for electrical conductors, comprising a spark gap formed between a conductive plate and a fluid discharging nozzle delivering a high resistance stream of water in proximity to said plate but normally out of contact therewith, and a second stream of water of larger cross-section connecting said nozzle to ground.

In witness whereof, I have hereunto set my hand this 3rd day of January, 1907.

STEPHAN SCHNEIDER.
